(57) **CLAIM**

The ornamental design for a foot peg device for a wheeled vehicle, as shown and described.

DESCRIPTION

FIG. 1 is a perspective view of a foot peg device for a wheeled vehicle, showing my new design, with a connector for coupling the device to the left side of a wheeled vehicle shown in phantom;

FIG. 2 is a top plan view thereof;

FIG. 3 is a bottom plan view thereof;

FIG. 4 is an end view thereof;

FIG. 5 is an end view thereof;

FIG. 6 is a front elevational view thereof; and,

FIG. 7 is a rear elevational view thereof.
